ATTORNEY.

UNITED STATES PATENT OFFICE

TROFINI H. OLHOW, OF ST. PAUL, MINNESOTA

VEHICLE CURTAIN ROLLER

Application filed March 14, 1928. Serial No. 261,546.

My invention relates to window-screen curtains particularly of a type suited for use in motor vehicle windows and also useful in railway coaches or other passenger carrying vehicles.

The main object is to provide a simple and efficient screen curtain roller and mounting therefor, the free end of such curtain being fixed to the upper edge of a vertically movable window pane such as used in motor vehicles. Further objects and advantages of this device are fully set forth in the following specification reference being had to the accompanying drawing, in which,

Fig. 1 is a central cross sectional elevation of my improved screen device in operative position adjacent a window opening of a motor car.

Fig. 2 is a longitudinal partly sectional top view of my device alone with the screen element omitted.

Fig. 3 is an approximately full size cross sectional view of the roller of my device about as on line 3—3 in Fig. 2 and showing the manner of attaching a shade to it.

Fig. 4 is a face view of Fig. 3, illustrating only a portion of the telescoped parts of my roller.

Referring to the drawing by reference numerals 5 designates the wall of an automobile at a window opening of which 6 is the lintel. 7 are the opposite vertical guides in the vertical frame members 9 of the window for guiding the vertical edges of the pane 8 adjustable vertically in the window frame by any suitable means (not shown) used for auto windows (see Fig. 1).

My device comprises an elongated sheet metal frame 10 of about L-shape in cross section and having integral transverse walls 10A which may each have a downward extension 10A' adapted to be secured as the screws 11 to the opposite window frame members 9 in such a manner as to hold the frame 10 with its open side adjacent the upper edge of pane 8 when the latter is in its closed position (see Fig. 1). 12 are upwardly opening notches in the end walls 10A both adapted to simultaneously receive the flattened aids 13A of a pair of spring rods 13 protruding one from

each end of my tubular telescopic curtain roller 14—15 of which 14 is the right hand and 15 the left hand inner member slidably insertable into the former (see Fig. 2). The outer ends of the roller each have a fixed end 55 piece or web 16 bored centrally and serving as a bearing for rod 13 which extends inwardly and carries at its inner end a fixed washer 17 retaining the inner end of rod 13 concentric within the tube. About each rod 13 I provide a retrieving coil spring 18 with one end fixed to washer 17 as 18A (Fig. 2) and its outer end fixed to inner side of web 16 as at 18B. The telescoped parts of roller 14—15 are slidably keyed together by providing in member 15 a longitudinal exterior key 15K punched outwardly from the metal of the tube (see Fig. 3) and slidably engaging in a corresponding slit 14S in tube 14. It will be thus readily understood that the roller 70 14—15 is adjustable in length according to length of frame 10 and the latter is of course made to correspond to the width of window opening.

As above described it is clear that the retrieving springs act simultaneously on both ends of the roller 14—15 instead of on one end as hitherto in curtain rollers. The main object of this dual retrieving action is to maintain an even tautness of the curtain 19 80 secured on the roller by means presently to be described, said curtain extending forward and down from the top of the roller and to the upper edge part of the pane 8 to which it is secured by any suitable means such as 85 an elongated inverted shape metal clip 20 (see Fig. 1).

In Figs. 3 and 4 I have illustrated the means and method of securing the curtain to the roller 14—15. Said means consist of 90 providing transverse shaped prongs 21 in suitable numbers longitudinally of the two tubular members 14—15 each said prong punched in the metal of which the tube is made and normally in a curved plane coinciding with the curvature of the tube. To secure the curtain these prongs are first simply forced outwardly and tangentially of the roller, as shown in Fig. 3, with any suitable tool. The edge portion of screen 19 95

is then pressed on to the prongs and toward the bases of the prongs as illustrated in Fig. 3 after which the said prongs are hammered back to original position, the curtain being thus not only retained by the prongs but depressed and retained under every one of them.

It is obvious of course that said curtain fastening takes place only when the length of roller has been determined and the tube sections 14-15 have been telescoped accordingly.

In Fig. 1 is clearly shown that I provide the lower front part of the frame 10 with an integral vertical flange 10F the front side of which is preferably provided with a strip 22 of rubber or other suitable material, the curtain bearing continuously against this between the roller and the upper edge of the pane 8. Thus when the pane is raised or lowered the curtain occupies any space above the pane and is kept clear of foreign matter by brushing against the strip 22. The weight of the pane moving downwardly to any position pulls the curtain down with it and a taut condition is further attained because the unrolling curtain pulls against the resistance of the retrieving springs 18. The latter resistance is not sufficient to prevent downward movement of the pane but it is obvious that in raising the pane from a lowered position the springs 18 roll up the curtain in taut condition.

I prefer to use a curtain of fine-mesh woven wire which is desirable not only for its transparent property but because it excludes ordinary dust, grains of sand and ordinary rain drops from the interior of the vehicle. Thus it will be seen that for example, in an automobile provided with my curtains, visibility is not reduced, the windows may be left open and dust and sand or rain drops cannot enter the car and besides these added comforts in driving the curtains are of course useful for keeping out insects when the car is used for sleeping quarters.

I claim:

A curtain roller of the class described with spring retrieving means and means for removably holding a curtain; said roller comprising tubular telescopic sections and key means on one of said telescopic sections for holding them fixed to each other in any selective telescoped position, said key means comprising an elongated outwardly directed spline formed of the metal in the inner of the telescoped tubes, the outer tube provided with an elongated key slot slidably engaged by said key.

In testimony whereof I affix my signature.
TROFINI H. OLHOW.
